UNITED STATES PATENT OFFICE.

CHARLES E. DEAN, OF CHICAGO, ILLINOIS.

DESIGN FOR A TABLE.

SPECIFICATION forming part of Design No. 22,461, dated May 23, 1893.

Application filed March 6, 1893. Serial No. 464,903. Term of patent 3½ years.

To all whom it may concern:

Be it known that I, CHARLES E. DEAN, a citizen of the United States, residing at Chicago, Illinois, have invented and produced a new 5 and original Design for Stands or Tables, of which the following is a specification, reference being had to the accompanying drawing, forming a part thereof.

The drawing represents a perspective view o of my table illustrating my design.

The leading feature of my design consists in the open work ends, which are formed of, or to present the appearance of, bamboo rods, showing their joints or enlarged knuckles, 5 and in the scroll shaped corner pieces and other features which give it a distinctive appearance to the eye.

The top of the table A is square in general outline, with rounded or scalloped corners, as o shown in the drawing. The bottom board, B, which is supported by the legs D, is also square in general outline, as shown in the drawing, and is provided at two of its opposing sides with the open work F. Between the

top piece A and the board B is arranged open 25 work E, composed of horizontal and vertical bars of bamboo, with the usual enlarged joints or knuckles. Under each of the corners of the top piece A, is arranged a corner piece C, of the scroll form shown in the drawing. The 30 ends of these corner pieces are provided with bases G, of the form shown. Along the straight edges of the top piece A are arranged scroll depending brackets g, of the form and with the ornamentation shown in the drawing. 35 The whole stand being made in the manner stated appears of very light construction, and is distinctive on account of the appearance given to it by the enlarged joints or knuckles of the bamboo work. 40

I claim—

The design for a table herein shown and described.

CHARLES E. DEAN.
